(57) **ABSTRACT**

A flashlight assembly includes an outer housing, an inner housing received in the outer housing, a cover partially received in the outer housing, and a base disposed in a top of the outer housing. The base has a protrusion extended into the inner housing. The base has two side grooves respectively defined in a lateral of the protrusion. The inner housing has two male projections. The cover has two female recesses. Each male projection engages with one of the two female recesses. The cover has two side protrusions. Each side protrusion engages with one of the two side grooves. The outer housing, the inner housing, the cover, and the base are firmly assembled.

FLASHLIGHT ASSEMBLY

BACKGROUND OF THE INVENTION

1. Field of the Invention

The present invention relates to a flashlight, and more particularly to a flashlight assembly which is assembled without any screw fittings.

2. Description of Related Art

A conventional flashlight in accordance with the prior art comprises a handle portion, a battery set, a lamp unit, and a head portion. The battery set is assembled with the handle portion by multiple screws. The lamp unit is assembled with the head portion by the other multiple screws. The head portion and the handle portion are assembled threaded. The screw fittings reduce the speed of assembling and increase the cost of material. Furthermore, the threaded fittings are loosed by vibrations such that the conventional flashlight structure is unstable.

The present invention has arisen to mitigate and/or obviate the disadvantages of the conventional flashlight.

SUMMARY OF THE INVENTION

The main objective of the present invention is to provide an improved flashlight assembly, in that a flashlight assembly which is assembled without any screw fittings is acquired.

To achieve the objective, the flashlight assembly includes an outer housing, an inner housing, a base, and a cover. The outer housing has a first receiving space defined in one end thereof and a first opening defined in a top thereof. The first opening is communicated with the first receiving space. The inner housing is received in the first receiving space. The inner housing has a second receiving space defined in one end thereof and a second opening defined in a top thereof. The second opening is communicated with the second receiving space and corresponding to the first opening. The inner housing has two male projections respectively extended from a lateral thereof. The base is partially received in the first opening. The base has a protrusion extended therefrom. The protrusion protrudes into the second receiving space via the first opening and the second opening. The protrusion has two side grooves respectively defined in a lateral thereof. The cover is partially received in the first receiving space. The cover has an insertion portion extended from one end thereof. The insertion portion is disposed between the inner housing and the outer housing. The insertion portion has two female recesses respectively defined in a lateral thereof. Each female recess is corresponding to one of the two male projections. The cover has a third opening defined in a top thereof and corresponding to the first opening and the second opening. The cover has two side protrusions respectively extended from a lateral of the third opening. Each side protrusion is corresponding to one of the two side grooves. Each male projection engages with the corresponding female recess. Each side protrusion engages with the corresponding side groove.

Further benefits and advantages of the present invention will become apparent after a careful reading of the detailed description with appropriate reference to the accompanying drawings.

BRIEF DESCRIPTION OF THE DRAWINGS

FIG. 1 is an exploded perspective view of a flashlight assembly in accordance with the present invention;

2

FIG. 2 is a partial exploded perspective view of the flashlight assembly in accordance with the present invention, showing the outer hosing, the inner housing, and the positioning plate;

5 FIG. 3 is an assembled perspective view of the flashlight assembly in accordance with the present invention in FIG. 2;

FIG. 4 is a partial exploded perspective view of the flashlight assembly in accordance with the present invention, showing the outer hosing, the base, and the button assembly;

10 FIG. 5 is an assembled perspective view of the flashlight assembly in accordance with the present invention in FIG. 4;

FIG. 6 is a partial exploded perspective view of the flashlight assembly in accordance with the present invention, showing the outer hosing and the cover;

15 FIG. 7 is an assembled perspective view of the flashlight assembly in accordance with the present invention in FIG. 6;

FIG. 8 is a partial exploded perspective view of the flashlight assembly in accordance with the present invention, showing the outer hosing and the handle;

20 FIGS. 8A-8C show the operation of the flashlight assembly in accordance with the present invention, showing the assembling of the outer hosing and the handle;

FIG. 9 is an assembled perspective view of the flashlight assembly in accordance with the present invention;

25 FIG. 10 is a cross sectional side plane view of the flashlight assembly in accordance with the present invention; and

FIG. 11 shows that the flashlight assembly in accordance with the present invention is connected to a bicycle handlebar.

30 DETAILED DESCRIPTION OF THE INVENTION

Referring to the drawings and initially to FIGS. 1-10, a flashlight assembly in accordance with the present invention comprises an outer housing 1, an inner housing 2 connected to the outer housing 1, a base 3 connected to the outer housing 1, a cover 4 connected to the inner housing 2, and a handle 5 connected to the outer housing 1.

The outer housing 1 has a first receiving space 11 defined in one end thereof and a first opening 12 defined in a top thereof.

40 The first opening 12 is perpendicular to the first receiving space 11 and communicated with the first receiving space 11. The first receiving space 11 is provided for receiving the inner housing 2 and the cover 4. The first opening 12 is provided for partially receiving the base 3. The outer housing 1 has a button recess 133 defined in the top thereof for receiving a button assembly 13. The button assembly 13 includes a button 131 and a spring 132. The spring 132 has one end abutted against a bottom of the button recess 133 and the other end abutted against an underside of the button 131 for providing a resilient force to the button 131. The button 131 has two hooks 1311 respectively extended from one end thereof. The hooks 1311 engage with the button recess 133 such that the button 131 is reciprocally moveably received in the button recess 133.

The inner housing 2 is received in the first receiving space 11. The inner housing 2 has a second receiving space 21 defined in one end thereof and a second opening 22 defined in a top thereof. The second opening 22 is perpendicular to the second receiving space 21 and communicated with the second receiving space 21. The second opening 22 is corresponding to the first opening 12 such that the base 3 is partially received in the second opening 22. The inner housing 2 has two installing bases 23 respectively extended from one lateral of the second opening 22. Each installing base 23 has two first projections 231 respectively extended from one end thereof.

50 The inner housing 2 has a third receiving space 24 defined in one end thereof and a third opening 25 defined in a top thereof. The third opening 25 is perpendicular to the third receiving space 24 and communicated with the third receiving space 24. The third opening 25 is corresponding to the second opening 22 such that the base 3 is partially received in the third opening 25. The inner housing 2 has two second projections 26 respectively extended from one lateral of the third opening 25. Each second projection 26 has two second projections 27 respectively extended from one end thereof.

55 The inner housing 2 has a fourth receiving space 28 defined in one end thereof and a fourth opening 29 defined in a top thereof. The fourth opening 29 is perpendicular to the fourth receiving space 28 and communicated with the fourth receiving space 28. The fourth opening 29 is corresponding to the second opening 22 such that the base 3 is partially received in the fourth opening 29. The inner housing 2 has two third projections 30 respectively extended from one lateral of the fourth opening 29. Each third projection 30 has two third projections 31 respectively extended from one end thereof.

60 The inner housing 2 has a fifth receiving space 32 defined in one end thereof and a fifth opening 33 defined in a top thereof. The fifth opening 33 is perpendicular to the fifth receiving space 32 and communicated with the fifth receiving space 32. The fifth opening 33 is corresponding to the second opening 22 such that the base 3 is partially received in the fifth opening 33. The inner housing 2 has two fourth projections 34 respectively extended from one lateral of the fifth opening 33. Each fourth projection 34 has two fourth projections 35 respectively extended from one end thereof.

65 The inner housing 2 has a sixth receiving space 36 defined in one end thereof and a sixth opening 37 defined in a top thereof. The sixth opening 37 is perpendicular to the sixth receiving space 36 and communicated with the sixth receiving space 36. The sixth opening 37 is corresponding to the second opening 22 such that the base 3 is partially received in the sixth opening 37. The inner housing 2 has two fifth projections 38 respectively extended from one lateral of the sixth opening 37. Each fifth projection 38 has two fifth projections 39 respectively extended from one end thereof.

70 The inner housing 2 has a seventh receiving space 40 defined in one end thereof and a seventh opening 41 defined in a top thereof. The seventh opening 41 is perpendicular to the seventh receiving space 40 and communicated with the seventh receiving space 40. The seventh opening 41 is corresponding to the second opening 22 such that the base 3 is partially received in the seventh opening 41. The inner housing 2 has two sixth projections 42 respectively extended from one lateral of the seventh opening 41. Each sixth projection 42 has two sixth projections 43 respectively extended from one end thereof.

75 The inner housing 2 has a eighth receiving space 44 defined in one end thereof and a eighth opening 45 defined in a top thereof. The eighth opening 45 is perpendicular to the eighth receiving space 44 and communicated with the eighth receiving space 44. The eighth opening 45 is corresponding to the second opening 22 such that the base 3 is partially received in the eighth opening 45. The inner housing 2 has two seventh projections 46 respectively extended from one lateral of the eighth opening 45. Each seventh projection 46 has two seventh projections 47 respectively extended from one end thereof.

80 The inner housing 2 has a ninth receiving space 48 defined in one end thereof and a ninth opening 49 defined in a top thereof. The ninth opening 49 is perpendicular to the ninth receiving space 48 and communicated with the ninth receiving space 48. The ninth opening 49 is corresponding to the second opening 22 such that the base 3 is partially received in the ninth opening 49. The inner housing 2 has two eighth projections 50 respectively extended from one lateral of the ninth opening 49. Each eighth projection 50 has two eighth projections 51 respectively extended from one end thereof.

85 The inner housing 2 has a tenth receiving space 52 defined in one end thereof and a tenth opening 53 defined in a top thereof. The tenth opening 53 is perpendicular to the tenth receiving space 52 and communicated with the tenth receiving space 52. The tenth opening 53 is corresponding to the second opening 22 such that the base 3 is partially received in the tenth opening 53. The inner housing 2 has two ninth projections 54 respectively extended from one lateral of the tenth opening 53. Each ninth projection 54 has two ninth projections 55 respectively extended from one end thereof.

90 The inner housing 2 has a eleventh receiving space 56 defined in one end thereof and a eleventh opening 57 defined in a top thereof. The eleventh opening 57 is perpendicular to the eleventh receiving space 56 and communicated with the eleventh receiving space 56. The eleventh opening 57 is corresponding to the second opening 22 such that the base 3 is partially received in the eleventh opening 57. The inner housing 2 has two tenth projections 58 respectively extended from one lateral of the eleventh opening 57. Each tenth projection 58 has two tenth projections 59 respectively extended from one end thereof.

ond projections 241 respectively extended from one corner thereof. Each second projection 241 is corresponding to one of the four first projections 231 such that each second projection 241 engages with the corresponding first projection 231 to fasten the positioning plate 24 with the installing base 23.

The base 3 has an outer surface 31 to enclose the first opening 12. The base 3 has a protrusion 32 extended from an underside thereof and protruded into the second receiving space 21 via the second opening 22. The outer surface 31 has multiple embossments (not numbered) to radiate heat from LED lamp. The protrusion 32 has two side grooves 321 respectively defined in a lateral thereof.

The cover 4 is transparent. The cover 4 has an insertion portion 41 extended from one end thereof. The insertion portion 41 is disposed between the inner housing 2 and the outer housing 1. The insertion portion 41 has two female recesses 61 respectively defined in a lateral thereof. The inner housing 2 has two male projections 62 respectively extended from a lateral thereof. Each male projection 62 is corresponding to one of the two female recesses 61 such that the male projection 62 engages with the corresponding female recess 61 to fasten the cover 4 with the inner housing 2. The cover 4 has a third opening 42 defined in a top of the insertion portion 41 and corresponding to the second opening 22 and the first opening 12. The cover 4 has two side protrusions 43 extended from a lateral of the third opening 42. Each side protrusion 43 is corresponding to one of the two side grooves 321 such that each side protrusion 43 engages with the corresponding side groove 321 to fasten the cover 4 with the base 3.

The outer housing 71 has an annular protrusion 71 extended from one end thereof. The annular protrusion 71 has at least one male projection 711 inwardly extended therefrom. The handle 5 is provided to receive the battery set (not numbered). The handle 5 has an annular groove 72 defined in one end thereof and corresponding to the annular protrusion 71. The handle 5 has at least one sliding groove 721 and at least one female recess 722 both defined in a bottom of the annular groove 72. The at least one female recess 722 is communicated with the at least one sliding groove 721 and corresponding to the at least one male projection 711. When rotates the handle relative to the outer housing 1, the at least one male projection 711 moves along the sliding groove 721 and engages with the female recess 722 such that the handle 5 fastens with the outer housing 1.

Referring to FIGS. 2-9, the assembly of the flashlight assembly in accordance with the present invention is illustrated. The positioning plate 24 is mounted between the two installing bases 23. The inner housing 2 is received in the first receiving space 11 as shown in FIG. 3. The protrusion 32 of the base 3 protrudes into the second receiving space 21 via the first opening 12 and the second opening 22. The base 3 is partially received in the first opening 12 as shown in FIG. 5. The insertion portion 41 of the cover 4 is inserted into the first receiving space 11. Each male projection 62 engages with the corresponding female recess 61. Each side protrusion 43 engages with the corresponding side groove 321. Therefore the cover 4, the inner housing 2, the outer housing 1, and the base 3 are stably connected to each other as shown in FIG. 7.

The male projection 711 is corresponding to the sliding groove 721 and moves along the sliding groove 721 as shown in FIGS. 8A and 8B. When rotates the outer housing 1 relative to the handle 5, the male projection 711 engages with the female recess 722 as shown in FIG. 8C such that the outer housing 1 is stably connected to the handle 5.

Referring to FIG. 11, the flashlight assembly in accordance with the present invention is connected to a bicycle handlebar (not numbered). The flashlight assembly in accordance with the present invention is assembled without any screw fittings. Therefore, the structure is stable and easy to assemble.

Although the invention has been explained in relation to its preferred embodiment, it is to be understood that many other possible modifications and variations can be made without departing from the spirit and scope of the invention as hereinafter claimed.

What is claimed is:

1. A flashlight assembly comprising:
an outer housing having a first receiving space defined in one end thereof and a first opening defined in a top thereof, the first opening communicated with the first receiving space;

an inner housing received in the first receiving space, the inner housing having a second receiving space defined in one end thereof and a second opening defined in a top thereof, the second opening communicated with the second receiving space and corresponding to the first opening, the inner housing having two male projections respectively extended from a lateral thereof;

a base partially received in the first opening, the base having a protrusion extended therefrom, the protrusion protruded into the second receiving space via the first opening and the second opening, the protrusion having two side grooves respectively defined in a lateral thereof; and

a cover partially received in the first receiving space, the cover having an insertion portion extended from one end thereof, the insertion portion disposed between the inner housing and the outer housing, the insertion portion having two female recesses respectively defined in a lateral thereof, each female recess corresponding to one of the two male projections, the cover having a third opening defined in a top thereof and corresponding to the first opening and the second opening, the cover having two side protrusions respectively extended from a lateral of the third opening, each side protrusion corresponding to one of the two side grooves;

wherein each male projection engages with the corresponding female recess; each side protrusion engages with the corresponding side groove.

2. The flashlight assembly as claimed in claim 1 further comprising a positioning plate connected to the inner housing, the inner housing having two installing bases respectively extended from a lateral of the second opening, each installing base having two first projections respectively extended from one end thereof, the positioning plate having four second projections respectively extended from one corner thereof, each second projection corresponding to one of the first projections, wherein each second projection engages with the corresponding first projection such that the positioning plate is mounted between the two installing bases.

3. The flashlight assembly as claimed in claim 1 further comprising a handle connected to the outer housing, the handle having an annular groove defined in one end thereof, the handle having at least one female recess defined in a bottom of the annular groove, the outer housing having an annular protrusion defined in one end thereof, the outer housing having at least one male projection inwardly extended therefrom, wherein the at least one male projection engages with the at least one female recess such that the handle is stably connected to outer housing.

4. The flashlight assembly as claimed in claim 1 further comprising a button assembly partially received in the outer housing, the outer housing having a button recess defined in the top thereof, the button assembly including a spring received in the button recess and a button abutted against one end of the spring, the button having two hooks extended therefrom and engaged with the button recess.
